[57] CLAIM

The ornamental design for a portable power drive,
substantially as shown and described.

DESCRIPTION

FIG. 1 is a front, three-quarter perspective view of the driven portable power drive of the present invention as it is supported in its operating position on support legs (shown in phantom) which, per se, do not constitute a part of the design of the present invention;

FIG. 2 is a top plan view of the portable power drive;
FIG. 3 is a right side elevational view of the portable power drive shown in FIG. 2;

FIG. 4 is a left side elevational view of the portable power drive rotated 180 degrees;

FIG. 5 is a bottom plan view of the portable power drive;

FIG. 6 is a front end elevational view of the portable power drive as it is shown in FIG. 3; and

FIG. 7 is a rear end elevational view of the portable power drive as it is shown in FIG. 3.
